UNITED STATES PATENT OFFICE.

ARTHUR REGINALD ANGUS, OF WESTMINSTER, ENGLAND.

CONTROL OF TRAINS.

Application filed June 17, 1922, Serial No. 569,125, and in Great Britain August 30, 1913.

This invention relates to electrical train-controlling apparatus.

In such apparatus according thereto there are on a train an electromagnetic controlling means, relaying means adapted when continuously effectually energized to cause the continuous energization of the electromagnetic controlling means, and an oscillatory means adapted to have its movable portion oscillated by electricity passing through itself and by sufficiently rapid oscillation of its movable portion to cause to be induced in the relaying means current suitable for continuously effectually energizing the relaying means.

The invention, which comprises the various features set out in the claiming clauses hereof, is illustrated by the accompanying drawings, of which Fig. 1 is a diagrammatic representation of electrical apparatus carried by a train and Fig. 2 is a diagrammatic representation illustrating a modification of the apparatus shown in Fig. 1.

Alternating current from the means external to the train—for example track rails or a special conductor—induces corresponding alternating current in an induction device 1 (Fig. 1) which, if contacts 3 and 12 carried by but insulated from a switch arm 4 adapted to be in one or the other of two different positions in accordance with the direction of running of the train (as by being connected with the reversing gear of the locomotive) are in contact with contacts 5 and 11 respectively (the reversing gear of the locomotive being set say for the down journey), flows by way of a wire 2, the contacts 3 and 5, and a wire 6 to a coil 7, thence by way of a wire 10, the contacts 11 and 12, and a wire 13 back to the induction device 1; a condenser 73 connected across the wires 6 and 10 as shown is of such a value as to give this circuit a resonant frequency corresponding to the frequency of the inducing alternating current—for example, a frequency of six cycles per second—supplied for the purpose of enabling a train to proceed on the down journey. The coil 7 is pivoted between the poles 8 and 9 of a permanent magnet so as to be oscillatable by the induced alternating current and when oscillated by current of the resonant frequency, an arm 21 fixed to the coil 7 and carrying an insulated contact 22, causes the latter to make contact alternately with contacts 23 and 24, so that current flows alternately from a generator 25 by way of (a) wires 26, 27 and 28, to the primary winding 75 of a transformer 76, thence by way of wires 33 and 34, the contacts 23 and 22, and wires 35, 36, and 37 back to the generator 25 and (b) the wires 26, 27, and 38 to the primary winding 81 of a transformer 82, thence by way of wires 41, 43, and 44, the contacts 24 and 22, and the wires 35, 36, and 37 back to the generator 25. The circuits of the primary windings of the transformers 76 and 82 being continually made and broken by the oscillation of the arm 21, the resultant intermittent currents induce currents in the respective secondary windings which flow from (a) the secondary winding 77 of the transformer 76 by way of wires 78 and 29 to an electromagnet 30 and thence by way of wires 31 and 80 back to the secondary winding 77 and (b) the secondary winding 83 of the transformer 82 by way of wires 84 and 39 to an electromagnet 40 and thence by way of wires 41 and 86 back to the secondary winding 83. The electromagnets 30 and 40 are rendered slow-acting by being shunted with noninductive resistances 32 and 42 respectively, the value of each of which is such that the armatures 47 and 51 of the electromagnets 30 and 40 are held against their respective contacts 48 and 50 as long as the coil 7 continues to oscillate at a suitable speed; consequently current flows from the generator 25 by way of the wire 26, wires 45 and 46, the armature 47, the contact 48, a wire 49, the contact 50, the armature 51, wires 52 and 53 to an electromagnet 54, thence by way of wires 55, 57, and 58, and the wire 37, back to the generator 25. The electromagnet 54 is also rendered slow-acting by being shunted with a noninductive resistance 56 the value of which is equal to or approximately equal to that of the coil of the electromagnet 54. The energization of the electromagnet 54 causes its armature 60 to make contact with a contact 61 and a circuit is thus completed from the generator 25 to an electromagnet 63 which is adapted when energized to prevent its armature 65 which constantly tends to cause the production of a warning operation or a stopping operation on the train from causing the production of a warning operation or a stopping operation, the current flowing from the generator 25, by way of the wires 26 and 45, a wire 59, the armature 60, the contact 61, and a wire 62 to the electromagnet 63, thence by way of wires 64 and 58 and the wire 37 back to

the generator 25. Thus the restraint of the production of a warning operation or a stopping operation is effected on the train as long as the coil 7 continues to oscillate, which will be the case as long as the circuit of the coil 7 receives alternating current of the frequency for which it is resonant.

If the reversing gear of the train is set for the up journey the switch arm 4 is in the position in which its insulated contacts 3 and 12 make contact with contacts 20 and 14 respectively but not with the contacts 5 and 11 respectively and the restraint of the production of a warning operation or a stopping operation is effected correspondingly on the train if the alternating current supplied to the train from means external thereto is of the frequency for enabling a train to proceed on the up journey. This frequency differs from that used for the down journey and may, for example, be one of eight cycles per second. For the up journey of a train the current induced in the induction device 1 flows by way of the wire 2, the contacts 3 and 20, and a wire 19 to a coil 16, thence by way of a wire 15, the contacts 14 and 12, and a wire 13 back to the induction device 1; a condenser 74 connected across the wires 15 and 19 as shown is of such a value as to give this circuit a resonant frequency corresponding to the frequency of the inducing alternating current supplied for the purpose of enabling a train to proceed on the up journey. The coil 16 is pivoted between the poles 17 and 18 of a permanent magnet so as to be oscillatable by the induced alternating current and when oscillated by current of the resonant frequency, an arm 66, fixed to the coil 16 and carrying an insulated contact 67, causes the latter to make contact alternately with contacts 68 and 69 so that current is supplied alternately to the electromagnets 30 and 40 in a manner similar to that described with reference to the down journey, the wires 71, 70 and 72 for the up journey corresponding respectively to the wires 35, 34 and 44 for the down journey, and consequently the restraint of a warning operation or a stopping operation is effected on the train in a manner similar to that described for the down journey.

If the resonant frequency of the circuit to which the induction device 1 is connected by the switch arm 4 is different from the frequency of the inducing alternating current,—i. e., if the train is not set for running in the direction in which it is intended that it should run—the coil 7 or 16 as the case may be does not oscillate so as to enable its contact 22 or 67 to make contact alternately with contacts 23 and 24 or with contacts 68 and 69 respectively, so that the production of a warning operation or a stopping operation is not restrained on the train. The re-

straint of the production of a warning operation or a stopping operation is not effected on the train if the arm 21 or 66 of the coil 7 or 16, whichever is in circuit with the induction device 1, remains steady either (a) midway between its respective contacts or (b) in contact with either one of them since when the arm remains steady in either of those positions the circuit of either of the primary windings of the transformers 76 and 82 is alternately made and broken so that no current is induced in either of the respective secondary windings and consequently neither of the electromagnets 30 and 40 is energized, and the restraint is effected only when the arm 21 or 66 as the case may be oscillates at the frequency for which the circuit of its coil 7 or 16 is made resonant so as alternately to make contact with its respective contacts as hereinbefore described.

One of the electromagnets 30 and 40 can be omitted and reliance placed on the other electromagnet: in that case the maintenance of the energization of the electromagnet employed is dependent upon the production of alternating current in the secondary of the transformer in question by the transmission of the current in the primary; the contact of the armature of the electromagnet that is employed is of course permanently connected to the electromagnet 54.

In the example shown in Fig. 1 there are employed two polarized relays adapted to be put into the circuit of the induction device 1 alternately according to the direction of travel of the train by the switch arm 4 and having respective inductances and capacity devices 73 and 74 adapted for attuning to the two frequencies employed. According to the modification illustrated by Fig. 2, however, there may be a single polarized relay 87, 88, 89 and the switch arm 4 be adapted to include in circuit with the relay and the device 1 one or the other of two means, as condensers 90 and 91 of different capacities, adapted to attune the circuit of the relay to one or the other of the two frequencies according to the direction of travel of the train. As shown in Fig. 2, the switch arm 4 is adapted when the train is traveling in one direction to cause the contact 3 to be in contact with a contact 95 and a contact 92 carried by the switch arm 4 but insulated therefrom to be in contact with contacts 93 and 94 and thus to include the condenser 90 in a circuit parallelly with the relay and the device 1; and when the train is travelling in the opposite direction to cause the contact 3 to be in contact with a contact 98 and the contact 92 to be in contact with contacts 96 and 97 and thus to include the condenser 91 parallelly in circuit with the relay and the device 1.

In order to prevent the armature 65 from

being tampered with after it has assumed its danger position (after, it may be, it has opened the brake pipe) and in order nevertheless that the driver may be automatically enabled to restart the train when it is again satisfactory for the train to proceed the armature 65 and any part whereby it could be operated by a local source is enclosed, as shown in broken lines in Fig. 1, 10 in a locked box and means are provided for ensuring that when the armature is in a danger position it will be in such a position as to be attracted into a line-clear position by its magnet (in which it will close the 15 previously opened brake pipe).

In the case of the example of apparatus shown in Fig. 1 and the modification thereof illustrated by Fig. 2, it should be arranged that the coils of the polarized relays (Figs. 20 1 and 2) should not be adapted to be oscillated as the result of the vibration of the train at a speed suitable for maintaining the energization of the slow-acting electromagnets 30 and 40 or of the slow-acting electromagnet 30 or 40 if that alone be used.

The induction device 1 (Figs. 1, and 2) is diagrammatically represented as a single coil only but in order to obtain the best results there should be placed on the locomotive 30 and also if required on a vehicle or vehicles attached thereto a number of coils which may extend all along the locomotive and should be placed as close as practicable to the track rails and/or the conductor 35 arranged close thereto and of course on both sides of the locomotive if the rails on both sides of the track are to be employed.

Conductive means, such as one or more than one brush, contacting device, or shoe, 40 may be placed on the locomotive and also if required on a vehicle or vehicles attached thereto so as to be in contact with track rails and/or one or more than one axle and/or with wheels or with a special conductor adjacent 45 to the track rails whereby current may be received conductively by the train apparatus and effects and operations may be thereby produced on the train after the manner hereinbefore described.

When the invention is to be used in connection with electric trains, if continuous unidirectional current is used for propulsion, alternating or pulsating unidirectional current may be used for the train-controlling 50 current; and if alternating or pulsating unidirectional current is used for propulsion, alternating or pulsating unidirectional current of a frequency or frequencies different from that used for propulsion may be used 55 for the train-controlling current; and any known means may be employed for preventing or limiting interference between the propulsion current and the currents used for the purposes of this invention. Except in the 60 cases in which a special conductor adjacent

to the rails is employed for the purposes of this invention in lieu of track rails, the current or currents supplied to the train for the purposes of this invention is or are preferably supplied by means of transformers or induction coils preferably at higher voltage or voltages than the propulsion current.

What I claim is:

1. Electrical train-controlling apparatus comprising on a train an electromagnetic 75 controlling means, relaying means adapted when continuously effectually energized to cause the continuous energization of said electromagnetic controlling means, and an oscillatory means adapted to have its movable portion oscillated by electricity passing through said oscillatory means and by sufficiently rapid oscillation of said movable portion to cause to be induced in said relaying means current suitable for continuously 80 effectually energizing said relaying means.

2. Electrical train-controlling apparatus comprising on a train electromagnetic controlling means, relaying means adapted on becoming effectually energized to move its 90 movable portion into a definite position and when continuously effectually energized to maintain said movable portion in said definite position and adapted only when said movable portion is maintained in said definite position to effect the continuous energization of said electromagnetic controlling means, and an oscillatory means adapted to have its movable portion oscillated by electricity passing through said oscillatory 100 means and by sufficiently rapid oscillation of said movable portion to cause to be induced in said relaying means current suitable for continuously effectually energizing said 105 relaying means.

3. Electrical train-controlling apparatus comprising on a train an electromagnetic controlling means, relaying means adapted when continuously effectually energized to cause the continuous energization of said 110 electromagnetic controlling means, an oscillatory means adapted when suitably energized to have its movable portion oscillated and by sufficiently rapid oscillation of said movable portion to cause to be induced in said 115 relaying means current suitable for continuously effectually energizing said relaying means, and a direction-corresponding part adapted to occupy two different positions according to opposite directions of running of said train and adapted in each of said 120 two positions to include said oscillatory means in a circuit of such resonance as to enable said oscillatory means to be suitably energized by a current of a frequency not suitable for the energization of said oscillatory means in the case of the occupation of the other of said two positions by said direction-corresponding part.

4. Electrical train-controlling apparatus 130

comprising on a train an electromagnetic controlling means, a slow-acting first relaying means adapted when continuously effectually energized to cause the continuous energization of said electromagnetic controlling means, a second relaying means adapted when continuously effectually energized, to cause the continuous effectual energization of said first relaying means, and an oscillatory means adapted to have its movable por-

tion oscillated by electricity passing through said oscillatory means, and by sufficiently rapid oscillation of said movable portion to cause to be induced in said second relaying means current suitable for continuously effectually energizing said second relaying means. ¹⁵

Signed at London, England, this 6th day of June 1922.
